UNITED STATES PATENT OFFICE.

JOHN C. DEAGAN, OF CHICAGO, ILLINOIS.

MUSICAL INSTRUMENT.

SPECIFICATION forming part of Letters Patent No. 674,604, dated May 21, 1901.

Application filed January 17, 1901. Serial No. 43,564. (No model.)

To all whom it may concern:

Be it known that I, JOHN C. DEAGAN, a citizen of the United States, residing at Chicago, in the county of Cook and State of Illinois, 5 have invented a certain new and useful Improvement in Musical Instruments, (Case No. 1,) of which the following is a full, clear, concise, and exact description.

My invention relates to musical instruments of the class known as "xylophones" or "marimbas," in which the musical tones are produced by vibrating bars of steel or wood arranged side by side and tuned to a scale. In such instruments the bars are usually set in vibration by percussion, as by striking them with a cushioned mallet. My invention is of especial value in connection with steel-bar marimbas having resonator-tubes below the bars to strengthen the tones.

20 The principal feature of my invention is the means which I have provided whereby tones of different length or quality may be obtained from the same instrument. This consists, generally speaking, in changing the support of the vibrating bars, as from points on the natural nodal lines to points a little removed from such nodal lines, and I have provided two ways in particular for thus changing the points of support. One way is 25 to provide a supplemental supporting-rail which may be raised or lowered to take the support of the bars upon itself or to transfer them to another bar, which will support them at a different point. Another way is by loosely 30 securing the bars to one of the rails by pins passing through comparatively large holes in the bars and constructing the supporting-framework in such a way that one of the rails upon which the vibrating bars rest may be 35 raised higher than the other to throw a part 40 of the weight of the bars upon the pins.

Other features of the invention are a new mounting for the bars whereby they may be played upon by a resined bow as well as by 45 mallets, an improved mounting for the resonator-tubes, and various minor structural improvements, which will hereinafter be pointed out.

I will describe my invention particularly 50 by reference to the accompanying drawings, and the particular features or combinations

of parts which I believe to be novel will be set forth in the appended claims.

Figure 1 is a perspective view of a steel-bar marimba embodying my invention. Fig. 2 is 55 an end view thereof with some parts broken away, showing how the frameworks which support the two sets of vibrating bars may be rotated to various angular positions. Fig. 3 is a vertical sectional elevation of the instrument. Fig. 4 is a detail sectional view illustrating the mounting of a supplemental supporting-rail for the vibrating bars. Fig. 5 is a plan view of one end of the instrument. Fig. 6 is a detail view showing a portion of 60 one of the bars having a hole therein and a cushioned pin or hook passing through the hole and into the supporting-rail for holding the bar in place, and Figs. 7 and 8 are fragmentary views showing how the supplemental 65 supporting-rail may be adjusted to a position different from that in which it is shown in the other views.

The same letters of reference are used to indicate the same parts wherever they are 70 shown.

In the instrument shown in the drawings, which, as before stated, is a steel-bar marimba with tubular resonators, there are two rows or sets of the vibrating bars *a*, each row being carried by an independent quadrilateral framework *b*, which is rotatably mounted in wooden end pieces *c c* of a steel standard *d*. In one of the frames the bars are tuned to a 80 diatonic scale, while on the other they are 85 tuned to the half-notes, both sets together thus giving the complete chromatic scale.

The frameworks *b b* are trapezoidal in shape, the non-parallel sides *b b'* of the trapezoid being elongated to form supporting-rails, across which the steel bars rest. The ends *b b'* of each frame are provided with threaded trunnion or pivot bolts, which are passed through holes in the end pieces *c c* of the supporting-standard and form a mounting for the frame, whereby it may be tilted to various angular positions. At the left-hand end piece *c*, as seen in Fig. 1, the trunnion-bolts *b b'* of the two frames are passed through long slots *c c'*, through which they may be moved and adjusted toward or from each other. This is a convenience when the

two frames are both to be rotated to the position of the one shown at the left in Fig. 2 to bring the two rows of plates, which would then be hanging vertically, into substantially parallel planes. When rotated to such positions, the instrument may be played by drawing a resined bow across the upper ends of the steel bars to throw them into vibration. The outer edges of the bars are lowered a little, as shown, to prevent the bow from slipping off. Thumb-nuts are provided for the threaded bolts $b^4 b^4$ to fasten the frames in any desired angular position, and cleats $c^2 c^2$ are provided upon the end pieces c , against which the ends of the frames abut when rotated ninety degrees and move toward one another through the slots c' . These cleats assist the thumb-nuts in holding the frames in the position to which they have been moved, and their function will be made clear by referring to Fig. 2.

As supplemental supporting-rail b^2 is mounted in each trapezoid frame alongside one of the main rails b . This supplemental rail is arranged to slide up and down in the end pieces, so that it may be moved up to support the bars or not, as may be desired. In Figs. 7 and 8 I have shown it in an elevated position, lifting the bars clear of the rail b and taking their support upon itself. A sliding catch b^5 is mounted at each end of this movable rail, which may be grasped to lift the rail and then pulled out, as shown in Fig. 8, to lock the rail in its elevated position.

The resonator-tubes $e e$ underneath the vibrating bars $a a$ are riveted between two steel tie-rails $f f$, which unite and support them. These tie-rails f are suspended from the end pieces $b^3 b^8$ of the trapezoid frame, as shown most clearly in Figs. 3 and 5. At the smaller end of each trapezoid these supporting-rails rest in recesses in the end of the framework, while at the larger end they are sustained by a pivoted cleat g , fastened by screws $g' g'$ to the inner surface of the frame end. Leather buffers $i i$ are provided in the ends of the frame, against which the tie-rails are held to prevent rattling or undue vibration.

The resonator-tubes are provided with adjustable plugs e' in the interior to regulate the length of the vibrating air-column, as described in a patent granted to me March 6, 1900, No. 644,817.

Felt cushion-strips are provided upon the upper edges of the side supporting-rails $b b'$ and the supplemental rail b^2 , so that a clear mellow tone will be produced free from all harshness or rattling.

Each of the bars $a a$ is held in place by three hooked pins $h h' h'$, one of said pins h passing through a hole a' in the bar near its outer end into the side supporting-rail b' and the other pins embracing the other end of the bar, being screwed on either side thereof into the rail b . These hooks do not engage the bar tightly, but serve merely as guides or sup-

ports to keep it in place upon the instrument. The pins $h' h'$ are provided with tubular soft-rubber sleeves or buffers. Upon the pins h , which pass through the holes in the bars, I provide in some cases hard-rubber washers, or I may leave them bare. This is to deaden or damp the vibrations to produce a short tone more readily when the bars rest upon the pins. Preferably for the bars of higher tone I provide the pins with soft-rubber buffers h^2 , stuck on one side of the pins only—the outside. These are merely to cushion the bars when they are hung vertically from the pins, as shown at the left in Fig. 2.

If steel bars, such as those described and shown, are struck while being supported at their nodal lines, the vibration will be continued for a few seconds after the stroke, producing a long hammering tone. In a musical instrument of the character described such a tone may frequently be used to good effect, but is not always desirable. For instance, light, quick, and delicate music cannot be well played with such long tones, because the notes will all be slurred or run together, and so produce a more or less confused jumble of sounds. The effect, in other words, is like that produced by playing the same music on a piano with the "loud pedal" on. I have found that by shifting the support of the vibrating bars to a point a little off the nodal line the vibration will be quickly checked or damped, so that a short sweet musical note will be obtained from each bar. I have therefore in my improved marimba provided two means for changing the support of the bars to damp their vibration, and so produce the desired short tone. The first consists simply in rotating the supporting-framework of the bars to an angular position, as shown at the right in Fig. 2. The hole a' , which is bored in each plate, is located so that its outer edge is just on the nodal line. The nodal line is indicated on the left-hand bar of the upper set in Fig. 5 by a dotted line. When the framework is horizontal, the bars are normally supported on their natural nodal lines by the felt-covered rails $b' b^2$; but when the frame is tilted to an angular position, as shown in the right-hand portion of Fig. 2, the first vibrations of the bars when struck cause them to slide down the incline a little way until they rest against the hooks h , which thus support the bars a little off the nodal lines. The vibrations of the plate are then checked or damped by this touch, so that a short tone is produced.

A second way of changing the quality of the tone, which may, if desired, be used in addition to the other, is by transferring the support of one end of each of the vibrating bars from the rail b^2 to the rail b , and vice versa. The rail b^2 normally supports the bars on their natural nodal lines, so that a long tone is produced when the bars are struck. When, however, the rail b^2 is lowered, as shown in Figs. 2 and 4, the bars are

transferred to the rail b , which supports them nearer their ends off of the nodal lines. When the bars are struck as thus supported, the vibrations are checked or damped and a short

5 tone produced. In the right-hand portion of Fig. 2 I have shown both the means of producing the short tone combined—that is, the framework is tilted so that the bars rest with the inner edges of the holes a' upon the hooks h and also the rail b^2 is lowered to transfer the support of the bars at the opposite ends thereof from the hole to the rail b off the nodal lines. In the left-hand portion of Fig. 2 I have shown the framework carrying the bars, 10 which are tuned to the half-notes, rotated in an opposite direction to that in which it would be tilted if it were in a position corresponding to that of the frame carrying the diatonic bars shown in the right-hand portion 15 of the figure. As shown in the left-hand portion, the bars hang vertically from the hooks h , so that the instrument may be played with a bow.

A feature of my invention which I consider 20 to be of especial importance is the location of the hole in the vibrating bar at a point such that the natural nodal line of the bar will be tangent to the edge of the hole. Heretofore in instruments of the character described where the nodal lines of the vibrating bars have been considered at all the holes have been bored centering on the nodal lines. My improvement has two advantages. When 25 the bars lie horizontally, they rest substantially upon their nodal lines and give a long tone; but when tilted they slide down until the pin touches the bar at a point distant the width of the hole from the nodal line, and, secondly, when the framework is rotated in 30 the opposite direction and the bars are hung vertically to be played upon by the bow, as shown in the left-hand portion of Fig. 2, they should have the greatest freedom of vibration, and in my invention they hang directly 35 upon their nodal lines. If the hole were bored centering on the nodal line, it is obvious that the bar would hang from a point removed from that line by a distance equal to half the diameter of the hole.

40 50 It is evident that modifications may be made in the structure shown without departing from the spirit of my invention, and I therefore do not desire to be understood as limiting myself to the precise construction shown; but,

Having described one embodiment of my invention, I claim as new and desire to secure by Letters Patent—

1. In a musical instrument of the class described, the combination with a series of vibrating bars a , of supports for said bars, and means for changing the points of support of the bars to change the quality of the tone, substantially as set forth.

65 2. In a musical instrument of the class described, the combination with a series of vi-

brating bars a , of supporting-rails b b' across which the bars rest, and a supplemental supporting-rail b^2 adapted to be adjusted to lift the bars from one of said rails b b' and support 70 the bars themselves along another line, whereby the tone given by the bars may be changed in quality by changing the support of the bars, substantially as set forth.

3. In a musical instrument of the class described, the combination with a series of vibrating bars, of a pair of side rails across which the bars lie, of pins passing through holes in said bars to one of the side rails, and a mounting permitting one of said side rails to 75 be elevated above the other, to throw a part of the weight of the bars upon the pins, whereby the bars may be caused to give tones of different qualities, substantially as described.

4. In a musical instrument of the class described, the combination with a series of vibrating bars a , of a supporting-framework having a pair of rails b b^2 across which the bars rest, each of said bars having a hole cut therein near a nodal line of the bar, the diameter of said hole extending substantially from the nodal line longitudinally of the bar, pins passing through the holes in said bars into one of the supporting-rails, and a mounting for the supporting-framework permitting 90 the same to be rotated to an angular position, whereby the support of said bars may be changed to cause them to produce tones of different qualities, substantially as set forth.

5. In a musical instrument of the class described, the combination with vibrating bars and a supporting-framework therefor, of a pair of rails f resting at their ends in the end pieces of the supporting-framework, and extending underneath the row of vibrating 100 bars, and resonator-tubes for said bars, fastened to the said rails f and lying between them, as described.

6. In a musical instrument of the class described, the combination with the vibrating 110 bars and the supporting-framework therefor, of resonator-tubes e for said bars, a pair of tie-rails f between which the resonator-tubes are fastened, and a removable cleat g secured to the inner side of one of the end 115 pieces of the framework, the rails f which support the resonator-tubes resting in recesses at one end of the supporting-framework and upon the cleat at the other end, substantially as set forth.

7. A vibrating bar for an instrument of the class described, said bar having a hole through the same, centered off the nodal line of the bar, with the edge of the hole on the nodal line, substantially as and for the purpose set forth.

8. In a musical instrument of the class described, the combination with a framework having supporting-rails, of vibrating bars a lying across said rails, pins fastening the 130 bars to one of the rails, said pins passing through holes in the bars, said holes being

centered near the nodal lines of the bar in such a location that the outer edges of the holes are substantially on the nodal lines, and a mounting for the framework to permit 5 the same to be tilted to cause the bars to rest upon the pins off the nodal lines, the framework being also adapted to be rotated in the opposite direction until the vibrating bars

hang from the pins resting on their nodal lines, substantially as set forth.

In witness whereof I hereunto subscribe my name this 15th day of January, A. D. 1901.

JOHN C. DEAGAN.
